(57) **CLAIM**

The ornamental design for a LED magnifier, as shown and described.

DESCRIPTION

FIG. 1 is a front, top perspective view of a first embodiment of a LED magnifier, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of detail "9" identified in FIG. 1;

FIG. 10 is a front, top perspective view of a second embodiment of the LED magnifier;

FIG. 11 is a rear, bottom perspective view thereof;

FIG. 12 is a front view thereof;

FIG. 13 is a rear view thereof;

FIG. 14 is a left side view thereof;

FIG. 15 is a right side view thereof;

FIG. 16 is a top view thereof;

FIG. 17 is a bottom view thereof; and,

FIG. 18 is an enlarged view of detail "18" identified in FIG. 10.

The dashed lines in the figures illustrate portions of the LED magnifier that form no part of the claimed design. The dash dot dash lines in FIGS. 1, 9, 10, and 18 indicate the boundaries of the enlarged views and form no part of the claimed design.
